UNITED STATES PATENT OFFICE.

CALVIN G. LITTLEFIELD, OF GLENCOE ILLINOIS

GAME APPARATUS

Application filed October 28, 1926. Serial No. 144,711

This invention relates to game apparatus. It has to do particularly with games of the sort that are played with playing cards, and which involve various combinations and sequences of play.

The general object of the invention is the provision of an apparatus with which games of the type indicated may be played, practiced or studied and various sequences of play compared.

A further object is the provision of an apparatus of the sort described which contains provision for the making of a record of the sequence of play of a hand so that different methods of playing a given hand may be studied and compared after it has been played in different fashions.

Another object is the provision of an apparatus which will facilitate the study and teaching of such games, through its provision for the keeping of a record of the sequence of play, said record being in a form permitting its separation from the rest of the apparatus, so that it may be submitted to an instructor for criticism or the like.

A further object is the provision of an apparatus of the sort described which is particularly adapted to the study and play of the game of whist, and the working out of problems in that game.

A further object is the provision of an apparatus of the sort described which admits of infinite variety in the hands played, and which may be operated rapidly and with facility.

Other and further objects of the invention will be pointed out or indicated hereinafter, or will be apparent to one skilled in the art upon an understanding of the apparatus or its employment in practice.

In the accompanying drawing forming a part of this specification, I illustrate one form in which the device and its component parts may be embodied, but it is to be understood that this is presented for purpose of illustration only, and is not to be construed in a fashion to limit the claims short of the true and most comprehensive scope of the invention in the art.

50 In the drawing,

Fig. 1 is a plan or top view of a game apparatus embodying the invention;

Fig. 2 is a detail showing one of the token holders with a token in place;

Fig. 3 is a perspective of a token holder; 55
Fig. 4 is a back view of a token holder
with a token in place as it appears in one
turned back position;

Fig. 5 is a perspective detail of one form of token; and

Fig. 6 is a detail of a record strip.

Various games, such as some of the games
customarily played with a strip.

customarily played with playing cards, involve a very great number of possible combinations and permutations of the cards.

binations and permutations of hands and sequences of play. An example of such games is the game of whist, which involves the playing of fifty-two cards at each deal from a distribution in four hands. Because

of the very great number of combinations and permutations offered by such a game, both as to the distribution of the cards and the sequence in which they may be played, and its present wide spread popularity, it

and its present wide spread popularity, it is given quite extensive and detailed study, and such, in fact, is necessary in order to acquire a mastery of the game. The present invention has been devised primarily for the purpose of facilitating the learning 75

the purpose of facilitating the teaching of the game, but it possesses further utility in the practicing of play and the working out of problems presented by various hand combinations, and in any of these uses it possesses 80

esses particular advantage by virtue of the physical association of the playing elements with a record portion whereon the sequence of play may be recorded to form the basis of a comparison between the different possible ways of playing a given hand. 85

In the illustrative form of device here shown, the numeral 10 designates a board of convenient size, adapted to rest on a table or the like and provided, along its four sides, with a series of token holders. Inasmuch as

the present example is designed for the game of whist, these token holders are arranged for the reception of tokens constituting the four hands, there being thirteen of said tokens in each hand and the tokens

100
tokens in each hand, and the tokens respectively corresponding to the respective cards of the whist deck. The form of token holder illustrated comprises a body portion 11 affording a pocket 12, and a U-shaped

nk portion 14 with which said body por- 105
on has hinge connection at one end. At its
her end the link has hinge connection with
wire or a rod 15 which is mounted flat
against the surface of the board. The token

holders for each hand are thus mounted in collateral relationship and in alignment and may be placed at various positions by the swinging of the link and the body portion, 5 without changing their order of arrangement on the board. For example, the holder designated X on Fig. 1 is shown in what I will designate the "hand" position, that is, a position which is indicative of its not as 10 yet having been played in the current deal. The holder designated Y in Fig. 1 is in a position which I will designate the "played" position, that is a position indicating that it is played in the current trick. The 15 holder designated Z in Fig. 1 is what I will term the "turned" position, that is, in a position indicating that it has been played in a preceding trick. In the position designated the "hand" position, the link 14 lies 20 against the surface of the board and projects from the anchor rod 15 toward the adjacent side of the board, while the body portion extends inwardly of the board from the end of the link. In the played position both 25 the link and the body portion are swung inwardly of the board and lie against its surface, while in the turned position, the link is swung inwardly of the board and the body portion swung on the link to a position toward the adjacent edge of the board. 30

The token holders are adapted for reception of the tokens, one of which is illustrated in Fig. 5. These are small flat pieces, each bearing the designation of a respective playing card, that illustrated in Fig. 2 being the ten of diamonds, and that in Fig. 5 being the jack of clubs. Each token has a tongue portion 16 which is adapted to fit in the pocket 12 of a body portion, in such fashion 35 that the token is securely held for movement with the holder, but may be withdrawn when desired, for the distribution and arrangement of the tokens in the various hands. Accordingly, the tokens may be assorted into 40 the various hands either by a blind deal, after being shuffled, or they may be distributed among the hands, for purposes of study or the working out of a problem, in accordance with a specified designation of the hands. 45

In association with each of the hands there is mounted on the board a record strip 17, which may be held in place by suitable push pins 18. This record strip preferably is arranged so that the holders overlie it when 50 they are in the hand position. These record strips may be of paper, and bear suitable designations such as "North," "South," "East" and "West," indicative of the respective hands. It may be advantageous to 55 provide them with record spaces, such as indicated by the numerals 1, 2, 3 and 4, wherein the various bids made on the hand may be recorded. These record strips also afford 60 space for the entering of the designation 65 of the cards in the hand, each marking being

placed in association with the holder carrying the token of that designation, as illustrated in association with the holder Y in Fig. 1. These strips also provide space for the entering of numerals designating the 70 tricks in which the tokens are played, such as the numeral 1 in association with the holder marked Z in Fig. 1.

In the use of the apparatus, the tokens are distributed to the four hands and, in the 75 event four persons are playing, the bidding will proceed in the customary fashion, each player entering his bid on the record strip pertaining to his hand. Then the play proceeds, the first player moving the selected 80 holder with its token to the played position, and the succeeding players moving the holders carrying the cards which they elect to play on that trick in a similar manner. Each player then enters on his record strip 85 the numeral 1, designating that that card was played in the first trick, the taker of the trick marking a circle about the numeral or otherwise indicating it as being the taking 90 card. When all four players have played on a trick, they all turn the played holders from the played position to the turned position, as designated at Z on Fig. 1. The play thus proceeds, the record being entered on 95 the record strip in association with the cards played on such tricks, viz, the numeral 2 being entered in association with the holder of the cards played on the second trick, the numeral 3 for those played on the third trick, and so on, and the played holders being turned to the turned position at the conclusion of the play of each trick. In this fashion the deal is played out and the record 100 of the play entered. For purposes of practice or comparison of different systems of play, the holders may then be returned to the hand position, the tokens remaining in place, and the same hands again played, the order of play of the respective cards being entered in a second line on the record strip as 105 before. It will be observed that in the hand position the holders or tokens cover the records of play previously entered, so that they cannot form a guide to the player or 110 players. 115

For purpose of study or working out of problems, the apparatus may be operated in the same fashion by a single player or by two players, so that a complete record is made of the order of play in the various instances. When it is desired to play a hand having a different distribution of cards, the record strips pertaining to the previous play are removed and replaced with others. The record strips, which thus carry on their faces 120 a designation of the cards in the hands and the sequence of play, are thus available for study, or for submission to an instructor as a basis for criticism or further instruction. 125

By virtue of the invention, therefore, the 130

student of the game is provided with an apparatus whereby the order of play and distribution of the cards may be closely studied and followed and records made with

5 certainty and facility as a basis for study or guidance. In the working out of a problem, for example, the student of the game is thus afforded means for his guidance in avoiding mistakes made in previous trials
10 and selection of alternative sequences of play.

What I claim is:

1. Game apparatus comprising the combination of movable token holders, tokens for connection to the holders, and a record sheet for association with the holders.

2. Game apparatus comprising the combination of token holders mounted in ordinal association, said token holders movable to different positions individually while maintaining their ordinal association.

25 3. Game apparatus comprising token holders mounted in ordinal association, said token holders movable individually to different positions while preserving their ordinal association, and a record sheet associated with said token holders.

4. Game apparatus comprising token holders mounted in ordinal association, said token holders movable individually to different positions while maintained in said ordinal association, and a record sheet associated with said token holders in a position wherein portions of it are covered by said token holders in one of their positions.

35 5. Game apparatus comprising the combination of a board, token holders mounted thereon in fixed ordinal association, said token holders being individually movable to different positions.

40 6. Game apparatus comprising a board having token holders mounted thereon in respective groups, said token holders being individually movable to different positions, and tokens for connection individually to respective token holders.

45 7. Game apparatus comprising token holders mounted in fixed ordinal association in respective groups, said token holders being individually movable, and tokens adapted for connection interchangeably with different holders.

50 8. Game apparatus comprising token holders mounted in fixed ordinal association in respective groups, tokens for connection interchangeably with different holders, and record sheets associated with respective groups.

55 9. Game apparatus comprising a board having token holders movably mounted in groups along its respective sides, and tokens adapted for connection interchangeably with the holders for movement therewith.

60 10. Game apparatus comprising token holders having fixed ordinal arrangement in groups, said holders being movable individ-

ually to three different positions, and tokens for connection individually to holders for movement therewith.

11. Game apparatus comprising token holders mounted in fixed ordinal association in groups, said token holders movable individually to three different positions, tokens adapted for connection individually with the holders, said tokens bearing designative markings, said markings being concealed when the holders are in one of said positions.

12. Game apparatus comprising token holders associated in groups, tokens connected with said holders individually, said tokens having designative markings, said token holders movable individually to different positions to expose and conceal said markings of their connected tokens.

13. Game apparatus comprising the combination of supporting means, a plurality of indicators mounted in series arrangement on the supporting means, each indicator being individually movable to different indicating positions, and a record sheet mounted on the supporting means in association with the indicators.

14. Game apparatus comprising the combination of a supporting means, a plurality of indicators mounted in series arrangement on the supporting means, each indicator being movable individually to different indicating positions, and a record sheet mounted on the supporting means so that portions of the sheet are covered by the indicators when in one position.

15. Game apparatus comprising the combination of a series of indicators mounted for swinging movement, each indicator having distinctive markings, each indicator swinging to different positions so as to expose or conceal said markings.

16. Game apparatus comprising the combination of a series of indicators mounted for swinging movement, each indicator having distinctive markings, each indicator swinging to different positions so as to expose or conceal said markings, and a record sheet associated with the indicators so that portions of the sheet are covered by the indicators when in one position.

17. Game apparatus comprising a board, a plurality of tokens having hinged connection therewith in series arrangement, said tokens adapted to be swung individually to different positions without varying their series relationship.

18. Game apparatus comprising a supporting means, a plurality of holders having hinged connection therewith in a series arrangement, a plurality of tokens adapted for connection interchangeably with respective holders and movable therewith to different positions individually without varying their series relationship.

19. Game apparatus comprising the com-

4
combination of supporting means, indicators having hinged connection therewith in fixed ordinal arrangement, said indicators being removable individually to three different positions without varying their ordinal relationship.

20. In game apparatus, a data sheet having markings thereon arranged in a collater-

al series, the respective markings being designative of respective cards of the whist deck, said strip affording entry spaces associated with the respective markings for reception of notations. 10

In testimony whereof I have hereunto subscribed my name.

CALVIN G. LITTLEFIELD.
